TILTABLE SUPPORT FOR USE IN TREATING
TEXTILE MATERIAL

Clarence Cochrane, Melrose, Mass.

Application July 24, 1947, Serial No. 763,422

8 Claims. (Cl. 68—197)

1

The present invention relates to supports for use in treating fibrous material such as wool, and is more particularly concerned with supports used in dyeing machinery, of the type sometimes referred to as cheeses or baskets.

The usual apparatus of this character comprises a perforated platform with a central standpipe, the platform being arranged to be received within a vat or kier. After insertion into the platform is piled with wool and the dyeing operation is carried out. Then the support is removed from the kier and the wool is usually pulled off by hand. There is frequently considerable difficulty in getting the wool off the support because of the fact that the wool fibers become matted together during the dyeing operation.

The principal object of the present invention is to provide apparatus whereby the support may be easily unloaded after the dyeing operation.

With this object in view, the present invention comprises a support for textile material having a number of hinged platform sections together with locking devices, whereby the platform sections may be held rigidly in place for the dyeing operation and may be easily released to dump the wool after dyeing.

In the accompanying drawings Fig. 1 is a plan view of a support according to the present invention; Fig. 2 is a side elevation of a portion of the apparatus, Figs. 3 and 4 are detail views of the locking devices; Fig. 4 being a section of line 4—4 of Fig. 3; and Fig. 5 is a detail on line 5—5 of Fig. 1.

As shown in Figs. 1 and 2, the support comprises a frame 6, a central hub 8 from which radiate a number of arms 10. The arms 10 support a rail 12, end rails 14, suitable internal bracing members 16, and an inner rail 17.

Rising from the hub is a perforated standpipe 18 of usual form and having a hoisting ring 19, as will be understood by those skilled in this art. All of the parts are preferably made of stainless steel.

Mounted on the frame 6 are two perforated platform sections, illustrated as semi-circular tables 20. Each platform section has suitable braces 21 on its underside and is provided with downwardly extending ears 24 embracing suitable ears 26 extending outwardly beyond the side rails 12 of the frame. Each platform section is mounted for pivotal movement on the ears 26 and to this end a rod 28 extends through all of them and is suitably secured at its ends as indicated by the nuts 30.

2

Each platform section is adapted to swing from a horizontal to an approximately vertical position and a suitable stop device is provided. This comprises two links 32 and 34, the former being connected to the under side of the platform section and the latter being pivoted to an ear 36 on the frame. The two arms are pivoted together at 38, and a stop pin 39 prevents motion of the section beyond the vertical position, as shown in Fig. 5. The folded position of the arms and the corresponding horizontal position of the table is illustrated in phantom in Fig. 5.

The platform sections may be locked in the following manner. At the inner edge of each platform section, there is a pair of downwardly extending ears 40 adapted to embrace one of the rails 16 when the section is in horizontal position. The ears 40 and the rails 16 have registering openings to receive a locking rod 42, the end of which is bent to form a handle 44. Each locking rod is free to slide in openings in the end rail 14 and a bracket 45. To unlock the platform the rod is simply withdrawn. When the rod is out, the handle portion 44 protrudes beyond the edge of the platform and hence it is impossible to lower it into the kier. The handle cannot be in place below the edge of the platform without assuring that the platform is locked. To prevent accidental dislodgement of the latch, the rod carries a locking dog 46 which is adapted to pass behind an ear 48 on the rail 17. In Fig. 1, the left handle is in locked position and the right handle is in release position.

Vertical dividing plates 50 are welded on each side of the standpipe 18 and between the rails 17, to prevent the wool fibers from matting and to keep the wool separate on the two platform sections, whereby it may be released from either or both of them at the same time.

In operation the support is lowered into the kier or vat with the platform sections locked. The wool or other fibrous material to be treated is piled up on both sections of the platform on opposite sides of the dividing plates 50. The dye liquid is then circulated in the usual manner as is well understood by those skilled in the art. At the completion of the dyeing operation, the support is removed, usually by an overhead crane, and is transported so that the two platform sections overlie the places where the wool is to be dumped. Preferably a truck is placed under each platform section. The sections may then be released by releasing the lock and pulling the rods out. The position of the hinge is preferably such that the platform sections are

slightly overbalanced when the locks are removed so that the wool will dump automatically. However, if desired, the balance may be such that the sections will not swing unless started by the operator; it will be appreciated that only a slight starting motion is necessary since as soon as the platform section is tipped slightly, the center of gravity of the mass of wool swings outwardly beyond the hinge line and carries the section to its limiting position, as indicated in Fig. 5. This avoids the necessity of pulling off the material by hand. After dumping, the platform sections are readily restored to horizontal position for a subsequent dyeing operation.

Having thus described the invention, I claim:

1. A support for treatment of fibrous materials comprising a rigid frame having side and end rails, a standpipe at the center of the frame, a radial dividing plate extending upwardly from the frame on each side of the standpipe, a plurality of perforated platform sections supported by the frame on opposite sides of the dividing plates, hinge means carried by the side rails of the frame and connected with the platform sections, said hinge means being spaced outwardly from the dividing plates, and a locking device for each section.

2. A support for treatment of fibrous materials comprising a rigid frame having side and end rails, a standpipe at the center of the frame, a radial dividing plate extending upwardly from the frame on each side of the standpipe, a plurality of perforated platform sections supported by the frame on opposite sides of the dividing plates, hinge means including ears carried by the side rails of the frame and by the individual platform sections, said hinge means being spaced outwardly from the dividing plates, and a locking device for each section.

3. A support for treatment of fibrous materials comprising a frame, a standpipe at the center of the frame, a plurality of perforated platform sections hinged on the frame and movable from a substantially horizontal position to a dumping position, and a locking device for each platform section, said locking device including a rod extending beyond the periphery of the section when the section is unlocked in order to prevent insertion of an unlocked support into a vat.

4. A support for treatment of fibrous materials comprising a frame, a standpipe at the center of the frame, a plurality of perforated platform sections hinged on the frame and movable from a substantially horizontal position to a dumping position, and a locking device for each platform section, said locking device comprising cooperating portions on the frame and the platform section with registering openings when the section is horizontal, and a locking rod to pass through the opening, the rod extending beyond the periphery of the section when the section is unlocked in order to prevent insertion of an unlocked support into a vat.

5. A support for treatment of fibrous materials comprising a rigid frame having side and end

rails, a standpipe at the center of the frame, a radial dividing plate extending upwardly from the frame on each side of the standpipe, a plurality of perforated platform sections supported by the frame on opposite sides of the dividing plates, hinge means including ears carried by the side rails of the frame and by the individual platform sections, and a locking device for each section, said locking device including a rod extending beyond the periphery of the section when the section is unlocked in order to prevent insertion of an unlocked support into a vat.

6. A support for treatment of fibrous materials comprising a rigid frame having side and end rails, a standpipe at the center of the frame, a radial dividing plate extending upwardly from the frame on each side of the standpipe, a plurality of perforated platform sections supported by the frame on opposite sides of the dividing plates, hinge means including ears carried by the side rails of the frame and by the individual platform sections, and a locking device for each section, said locking device comprising cooperating portions on the frame and the platform section with registering openings when the section is horizontal, and a locking rod to pass through the openings, the rod extending beyond the periphery of the section when the section is unlocked in order to prevent insertion of an unlocked support into a vat.

7. A support for treatment of fibrous materials comprising a rigid horizontal frame, a standpipe at the center of the frame, two semicircular perforated platform sections supported by the frame, dividing means including a vertical plate to separate the platform sections, hinge means carried by the frame and connected with the individual platform sections and spaced outwardly from the dividing means, and a locking device for normally retaining each platform section in horizontal position on the frame.

8. A support for treatment of fibrous materials comprising a rigid horizontal frame, a standpipe at the center of the frame, two semicircular perforated platform sections supported by the frame, dividing means including a vertical plate to separate the platform sections, hinge means carried by the frame for the individual platform sections and situated near the balance positions of the sections, and a locking device for normally retaining each platform section in horizontal position on the frame.
